UNITED STATES PATENT OFFICE

2,211,728

ELECTRICAL COIL INSTALLATION AND
FASTENER FOR THE SAME

Wilford C. MacFadden, Philadelphia, Pa., assignor to United-Carr Fastener Corporation, Cambridge, Mass., a corporation of Massachusetts

Application June 11, 1938, Serial No. 213,245

7 Claims. (Cl. 248—1)

My invention relates to a fastener member for securing electrical and the like units to a supporting structure and to installations of the same.

An object of my invention is the provision of a fastener member directed to an improvement over those fastener devices illustrated and described in connection with my copending applications, Serial No. 174,641, filed November 15, 1937, and Serial No. 193,473, filed March 2, 1938.

10 Another object of my invention is to provide a one-piece fastener member of improved construction adapted for use with an electrical unit, such as an assembly of an iron core with a coil form, whereby it serves not only to secure the coil form 5 to a supporting panel, but, also, to secure the iron core to the panel in a way to maintain the iron core in firm adjustable assembly with the coil form.

20 Other objects and purposes of my invention will be apparent from inspection of the drawing and specification hereinbelow set forth.

Referring to the drawing, in which I have illustrated a preferred embodiment of my invention:

25 Fig. 1 is a fragmentary front view of an installation comprising a supporting panel and a coil form and an iron core secured to the panel by means of my improved fastener member;

Fig. 2 is a view similar to Fig. 1 but with the 30 installation turned 90°;

Fig. 3 is a bottom plan view of the installation shown in Fig. 1;

Fig. 4 is a view similar to Fig. 2 showing the manner in which the iron core is moved into 35 cooperating fastener engagement with my improved fastener member;

Fig. 5 is a section taken along the line 5—5 of Fig. 4;

Fig. 6 is a section taken along the line 6—6 of Fig. 2;

Fig. 7 is a plan view of my improved fastener member per se;

Fig. 8 is a bottom view of my fastener member per se; and

Fig. 9 is a top view of my fastener member per se.

Referring to the drawing, I have shown a preferred installation comprising an electrical unit such as a coil form of the type commonly used in 50 radio apparatus. The coil form has a tubular-shaped outer covering 1 of cardboard or other relatively stiff material which is adapted to be wound with a wire coil (not shown) in the manner well known in the art. The unit is preferably secured to a supporting panel 2 by means of my

improved fastener member 3 in a manner fully set out in either one of my aforesaid co-pending applications so as to be fixed in upstanding relation to the panel. An iron core 4 is disposed within the coil form 1 and has a threaded shank 5 extending beneath the core through the support 2 into cooperating threaded engagement with portions of the fastener member 3 in a manner to be described. Thus the fastener member serves to secure the iron core to the support 2. At the same time the fastener member serves to maintain the iron core in adjustable assembly with the coil form so that the frequency calibration of the coil may be regulated by moving the iron core axially of the coil form and relative to the windings on the coil form, as will be understood by those skilled in the art.

Referring in detail to my preferred fastener member, I have provided one of simple construction which is preferably made of one piece of sheet metal. The fastener member has a base portion 6 which is bulged inwardly permitting a certain resiliency therein which aids to effect attachment of the coil form to the support. The base 6 has an aperture 7 therein (Figs. 3, 8 and 9) adapted to receive the shank 5 of the iron core upon attachment of the iron core to the support. Legs 8—8 extend from opposed ends of the base 6 and provide hook-like inwardly-extending portions 9—9 for engaging the coil form 1 through apertures 10—10 thereof to secure the coil form to the supporting panel. The inwardly-extending portions 9—9 are preferably cured at their outer ends (10a), as most clearly shown in Fig. 9, so that the coil form may be engaged therewith by a relative rotative movement in the manner described in connection with my co-pending application, Serial No. 193,473, filed March 2, 1938. An arm portion 11, integral with a longitudinal edge of the base 6 intermediate the ends thereof, extends beneath the base 6 on an opposite side thereof from the legs 8—8. The arm 11 has an inwardly-projecting portion 12 spaced from the base 6 and intersecting the opening 7 of the base for a purpose to be described. The arm 11 is relatively stiff, but may yield slightly during attaching engagement of the shank 5 of the iron core with the fastener member, as will be described.

Assembly of the component parts of my installation is a relatively simple matter and may be carried out through moving the arms 8—8 of the fastener member through the openings 13—13 of the support 2 so that the inwardly-extending portions 9—9 are disposed on one side of the

support, which may be called the upper side, and the base 6 is disposed on an opposite, or lower, side of the support. Next, the base 6 is substantially flattened by upward pressure exerted upon 5 its opposed ends and the coil form moved toward the fastener member so as to engage the hook-like portions 8 of one of the fastener legs 8-8 through one of the apertures 10 thereof. Next, the coil form is rotated in the manner described 10 in connection with my co-pending application, Serial No. 193,471, so as to engage the hook-like portion 8 of the other leg 8 with the coil form through the other aperture 10 thereof. When pressure for flattening the base 6 is released, opposite ends of the base move toward normal 15 position tending to pull the hook-like portions 9-9 toward the supporting panel 2 so as to engage them with material of the coil form adjacent the lower walls of the aperture 10-10, as most 20 clearly shown in Fig. 1. Thus the coil form is secured in firm attachment to the support. Although I have preferred to illustrate my improved fastener member in connection with a 25 relatively wide supporting panel having openings therein for receiving the legs 8-8 of the fastener member, it will be understood that my fastener member is equally useful in connection with a modified installation (not shown) wherein the supporting panel is of relatively narrow construction with the width thereof disposed entirely 30 between the legs 8-8 of the fastened member so that the legs 8-8 are disposed outside the lateral edges of the panel.

In assembling the iron core 4 with the coil 35 form, the iron core is moved into the open end of the coil form opposed to the end adjacent the support 2 and the shank 5 is passed axially of the coil form through a circular opening 14 of the panel 2 (Figs. 5 and 6) and the opening 7 of the 40 fastener base so that the shank abuts the inner surface 15 of the arm 11 of the fastener member intermediate the portion 12 and the junction of the arm with the base 6 of the fastener, as most 45 clearly shown in Fig. 4. After the coil form has been assembled as described thus far, it is loosely held within the coil form 1 in substantially central position relative to the walls of the form solely by loose engagement of the threaded shank 5 with the walls surrounding the opening 7 of the 50 fastener base (Figs. 4 and 5). As downward movement of the shank 5 of the iron core through the opening 7 of the base is continued, the shank 5 is engaged by the relatively stiff arm 11 of the fastener member. As a result of this engagement, 55 the shank 5 is moved laterally against the wall of the aperture 7 so that portions of the threads of the shank enter into cooperating threaded engagement with a portion of the wall of the aperture 7, as most clearly illustrated in Figs. 3 and 6.

60 At the time the shank 5 is in cooperative threaded engagement with the wall of the aperture 7, the iron core is inclined slightly as a result of pressure of the arm 11 upon the shank 5 with the result that the upper portion of the iron core is moved from substantially central position relative to the bore of the coil form 1, as shown in Fig. 4, into abutting relation with the inner side of the coil form, as most clearly shown in Fig. 2. When the iron core is in final attached position 65 70 with its shank in cooperative engagement with the wall of the aperture 7 of the fastener and its upper portion in engagement with the inner walls of the coil form, it is firmly maintained in assembly with the coil form and otherwise incapable of movement or vibration so as to cause 75

fluctuation in the calibration of the coil. The frequency calibration of the coil may be wilfully adjusted by turning the iron core so as to move it either up or down. This result is accomplished by reason of the fact that the shank 5 of the iron core remains in cooperating threaded engagement with the wall of the aperture 7 of the fastener base as long as the shank of the iron core is engaged by the innermost laterally-projecting point 12 of the arm 11. 10

Although I have illustrated and described a preferred embodiment of my invention, I do not wish to be limited thereby because the scope of my invention is best defined by the following 15 claims.

I claim:

1. In combination, a support having an opening therein, a tubular article disposed on one side of said support, a part disposed within said tubular article and a fastener member having an apertured base disposed on the other side of said support from said tubular article, attaching means extending from said base above said support and engaging said tubular article for securing the same to said support, said part within said tubular article having a shank extending through said support and the base of said fastener member, and said base having integral means in inter-engaging relation with said shank to maintain said part disposed within said article in assembly with said support. 20

2. In combination, a support having an opening therein, a tubular article disposed on one side of said support, a part disposed within said tubular article and a fastener member having an apertured base disposed on the other side of said support from said tubular article, attaching means extending from said base above said support and engaging said tubular article for securing the same to said support, said part within said tubular article having a shank extending through said support and the base of said fastener member, and said base having integral means in inter-engaging relation with said shank to maintain said part disposed within said article in assembly with said support. 30

3. In combination, a support having an opening therein, a hollow retainer member disposed on one side of said support, an article of manufacture disposed within said retainer member and a fastener member having a base disposed on the other side of said support from said retainer member, attaching means extending from said base above said support and engaging said retainer member for securing the same to said support, said base having an opening therein and an arm extending beyond one side of said base, said arm having a portion in alignment with the opening of said base, and said article of manufacture having a shank extending through said support and said opening of said fastener base, said shank having spaced laterally-projecting portions for engagement with the base of said fastener and said shank being engaged by said arm to move one of said spaced projecting portions thereof behind said base whereby said article is secured to said support in assembly with said retainer. 50

4. A fastener member for securing an article of manufacture to a support, said fastener having an apertured base portion, attaching means extending from said base for engaging said article to secure the same to said support, and an arm portion extending from said base having a 60 65 70 75 80 85 90 95 100

portion in alignment with said aperture of said base for engagement with a part to be extended through said aperture.

5. A fastener member for securing an article of manufacture to a support, said fastener having an apertured base portion, attaching means extending from opposite ends of said base for engaging said article to secure the same to said support and an arm portion integral with an edge 10 of said base between said ends, said arm having a portion in alignment with said aperture of said base for engagement with a part to be extended through said aperture.

6. A fastener member for securing an article of manufacture to a support, said fastener having an apertured base portion, attaching means extending from said base beyond a side thereof for engaging said article to secure the same to said

support, and an arm portion extending from said base beyond an opposite side thereof from said attaching means, said arm having a portion in alignment with said aperture of said base for engagement with a part to be extended through 5 said aperture.

7. A fastener member having a bulged base portion, leg portions extending from opposite ends of said base portion having portions at their free ends adapted to engage an article of manufacture for securing said article to a support, said base having an aperture therein and an arm integral with said base intermediate said legs, said arm extending beyond an opposite side of said base from said legs and having a portion in alignment with the aperture of said base substantially 10 as described.

WILFORD C. MacFADDEN.
